DISPENSER CONTROL MEANS

Joseph M. Gordon, South Bend, Ind., assignor
of one-half to Leland E. Line, South Bend,
Ind.

Application March 30, 1936, Serial No. 71,764

10 Claims. (Cl. 200—52)

This invention relates to dispenser controlling means, and particularly to means for controlling a pay-out or dispensing device associated with a coin operated amusement device.

5 Heretofore various types of controls have been used with dispensing devices associated with coin operated machines, but these have been of the type so associated with the machine as to be actuated only upon certain successful manipulations 10 or operations of the device dependent either upon skill or luck. It is the primary object of this invention, however, to provide a control device entirely disassociated from the normal operation or "play" of the machine, and which energizes a 15 dispenser in a predetermined manner dependent entirely upon the number of times the coin operated machine is operated, so that play of the machine is stimulated by the incentive incident to the possibility of obtaining a reward without regard to the character or value of the result of the operation of the machine per se.

A further object is to provide a control of this character including a counting device and means associated therewith for automatically energizing 20 a dispenser each time a predetermined number of operations of the machine has been counted.

A further object is to provide a control of this character with means for preventing repeated actuation of a dispenser.

25 Other objects will be apparent from the description and the appended claims.

In the drawing:

Figure 1 is a top plan view of a coin operated amusement device with parts thereof broken away to illustrate the application of the control device and dispenser thereto.

Figure 2 is a view of the control device in side elevation, and in inverted position.

Figure 3 is a bottom plan view of the control device with parts broken away to better illustrate the construction.

Figure 4 is a fragmentary top plan view of the control device illustrating the operation of the means for preventing repeated operations of the control.

Referring to the drawing, which illustrates the preferred embodiment of the invention, and particularly to Fig. 1, which illustrates the application of the control to one type of coin operated device; the numeral 10 designates a conventional coin operated amusement device of the "pin-ball" type, having a casing 11 with a transparent cover, and a game board 12 within the casing and adapted to be viewed through the cover. 45 The game device is provided with a projector 13

for propelling balls through a guideway 14 onto a playing area 15 of the game board which has a plurality of goals in the nature of ball-receiving apertures 16 therein. Suitable pins or other obstacles 17 are provided to render the operation of propelling the balls in a manner to lodge them in the apertures 16 difficult of accomplishment. Beneath the game board is slidably mounted a spring pressed secondary board 18 or plate 18 which has apertures 19 therein arranged in normally off-set relation to apertures 16 of game board 12 to trap the balls which lodge in said apertures 16. The plate 18 is slidable by the coin receiver 20 of the device to bring apertures 19 into registration with apertures 16 to 10 release the balls upon the insertion of each successive coin in the device. This construction is 15 all conventional in the art.

Suitably mounted within casing 10 is a dispensing or pay-out device, here illustrated diagrammatically at 21 and preferably of the electrically operated type. Also mounted within the machine is the control device diagrammatically illustrated at 22 and adapted to be actuated by a suitable actuating arm or member 23 carried by plate 18. One or more pairs of normally spaced spring contacts 24 are associated with the control device to be shifted into engagement thereby, and these pairs of contacts constitute control switches in the circuits 25 for actuating the dispenser 21 through electrical energy derived from any suitable source, here illustrated as a dry cell 26.

The control device 22 is mounted on a suitable plate like base 27 formed of insulating material and includes a flange 28 by which the base 27 may be mounted on the under side of game board 12 in laterally spaced relation to plate 18, and a vertical off-set portion 29 adjacent the side edge of plate 18, whereby the base proper is spaced below the plate 18, as illustrated in Fig. 3. 35 Mounted on the base 27 is a suitable frame of substantially U-shape in vertical section. Frame 30 includes spaced horizontal walls 31 and a vertical connecting wall 32 therebetween. The horizontal walls 31 are each of generally 40 curved outline and mount vertical shafts 33 and 34 between their end portions and a vertical shaft 35 between their center portions. Frame 33 is preferably mounted in spaced relation to base 27 by suitable bolts and nuts 36 having 45 spacers 37 associated therewith and interposed between the base and frame.

Journalized on the shaft 33 between frame walls 31 are a plurality of cooperating counter elements each comprising a ratchet wheel 38 and a 50

disc 39 fixedly connected together in concentric relation, with the disc 39 of substantially larger radius than the ratchet wheel. The number of these counter elements employed is optional, three being here illustrated. A spacer 40 is positioned between the group of counter elements and one frame wall 31 for the purpose of holding said counter elements in desired position longitudinally of shaft 33. Journaled on the shaft 35 are a plurality of pawls 41 equal in number to the counter elements and each adapted to lie flush with one face of a tooth of the complementary ratchet wheel. Each of these pawls 41 has a shoulder 42 normally positioned in substantially parallel relation to vertical wall 32 of the frame and borne against by one end of a coil spring 43 whose opposite end is seated in a suitable recess 44 formed in an interior enlargement 45 of said wall 32.

20 Journaled on the shaft 34 between spacers 46 is a lever 47 which has opposed free end portions 48 and 49. Lever end portion 48 is connected by a coil spring 50 with the vertical frame wall 32 to draw said end portion to the right as viewed 25 in Fig. 3, and this spring actuated lever movement is limited by engagement of a pin 51 carried by said lever portion 48 with the vertical frame wall 32. The lever end portion 49 carries a pin 52 parallel to shaft 34 on which is pivoted the 30 bifurcated end portion 53 of a pawl unit 54 which comprises integral pawls or fingers 55. The pawl fingers 55 are spaced apart and each is aligned with one of the ratchet wheels 38; and said fingers are of different lengths, as best illustrated in Fig. 35.3, with the longest thereof only being in normal engagement with its complementary ratchet wheel, being the lowermost as seen in Fig. 2. A coil spring 56 extends between pawl unit 54 and lever 47 to hold the former in operative relation to the ratchet wheel assembly. In constructions 40 where more than one ratchet wheel 38 is employed, all but one of said wheels are provided with a notch 57 between two of the teeth thereof, as best illustrated in Fig. 4, into which the 45 cooperating pawl may move to bring the next adjacent and shorter pawl into engagement with its ratchet wheel. In this way the second ratchet wheel is rotated only one step or notch for each rotation of the first ratchet wheel, and the third ratchet wheel is operated only one step or notch for each 50 complete rotation of the second, which occurs only when the notches 57 in the first and second ratchet wheels register in position to receive the ends of the cooperating pawls 55.

55 Fixedly mounted on the pivoted end of pawl unit 54 is a bracket 58 having parallel opposed ears 59 projecting therefrom to mount a pin 60 parallel to pin 52. On the pin 60 is pivoted one end of a plate 61 which is so positioned and of 60 such width as preferably to engage the periphery of each of the discs 39 in spaced relation to the ends of pawls 55. A spring 62 is connected at its opposite ends to plate 61 and vertical frame wall 32, and passes between the pawls 55.

65 One or more of the discs 39 have one or more pairs of pins 63 projecting radially therefrom in circumferentially spaced relation. As here illustrated, two of the discs are each provided with a pair of said pins. Of each pair of pins 63, one pin 70 is substantially longer than the other. The spacing of the pair of pins on each individual disc preferably differs from the spacing of the pins on the other discs, as best illustrated in Fig. 2, and for purposes to be hereinafter set forth.

75 The actuating member 23 carried by plate 18 is

preferably formed of sheet metal and comprises a base 64 secured to plate 18 in spaced relation to base 27, a perpendicular central portion 65, and an end portion 66 spaced from plate 18 and extending in normally spaced aligned relation to 5 the end 49 of lever 47.

One or more angle brackets 67 formed of insulating material and having elongated slots 68 in one flange thereof for the reception of suitable securing means 69, are adjustably secured in 10 face contacting engagement to the base 27 in spaced relation to the discs 39. The other or vertical flange of each of said brackets is preferably provided with a pair of spaced parallel vertical elongated slots 70 for the reception of means 15 71 by which the spring contact switches 24 are adjustably secured thereto. Each of the spring contact switches comprises a pair of normally spaced elongated spring plates 72 between one end of which is interposed a spacing layer of insulating material 73, and over the outer of which is disposed a second insulating layer 74. The free ends of the spring plates 72 extend in the direction of the discs 39, each being positioned opposite a disc which is provided with pins 63 and 25 terminating in spaced relation therefrom a distance less than the length of the long pins and greater than the length of the short pins of each pair of pins 63 on the complementary or associated disc 39. Connected to the outer end of 30 each contact 72 is one wire of one of the circuits 25.

The spacing of the long and short pins 63 of each pair on each disc is equal to the space between said long pin when positioned to flex spring 35 plates 72 into engagement, and a point adjacent and in front of the free end of plate 61.

The operation of the device is as follows: Each time the plate 18 is shifted by coin receiver 20, the end portion 66 of actuating member 23 is 40 longitudinally shifted therewith to engage the lever end 49 to pivot lever 47 against the action of spring 50 to thereby cause the longest pawl 55 to engage the first or primary ratchet wheel 38 one notch. The spring pressed pawl 41 cooperating 45 with said primary ratchet wheel serves to prevent backlash of said ratchet wheel and acts as a brake against spinning of said ratchet wheel by said pawl. Upon release of actuating member 23 the parts return to their normal position, the 50 engagement of pin 51 carried by lever 47 with frame wall 32 serving to prevent return of said lever 47 by spring 50 beyond a predetermined position adjusted to insure a subsequent operating throw of the lever just sufficient to enable pawl 55 to rotate ratchet wheel 39 one notch.

As the operation of the coin controlled machine continues, with actuation of the control device coincidentally with each actuation of the coin receiver, the ratchet wheels are rotated in the 60 well known manner of counting devices until the long pin 63 on one disc 39 is moved to a position illustrated in full lines in Fig. 4, to flex the spring contact plates 72 into engaging relation or closed-switch position to complete the circuit 25 65 to actuate dispenser 21. The same movement of said disc disposes the short pin 63 of the same pair forwardly of the front or free end of plate 61. Then upon the succeeding operation of the coin receiver to pivot lever 47 and pawl unit 54, 70 the plate 61 carried by the latter engages the short pin 63 and rotates said operating disc one notch to shift the long pin 63 past the spring contacts 72 to again open the switch formed thereby and thus prevent immediate repetition 75.

of the actuation of the dispenser as would otherwise occur by virtue of the normal stationary relation of the secondary discs until a predetermined number of operations of the primary disc have occurred. It will also be obvious that this arrangement is such that when the long pin 63 is shifted to a position immediately in front of the plate 61, said plate will engage it upon the succeeding actuation of the coin controlled device. 10 In this way, for each pin on each of the secondary discs, said discs are given one free or lost step movement. This requires compensation of the ratchet wheels of the secondary discs to provide the desired count between actuations of the dispenser. Thus, assuming it is desired to close the circuit to the dispenser 21 which is associated with the central disc once for each one hundred operations of the game device, and to close the circuit associated with the other secondary disc 20 once for each one thousand operations of the game device; the first or primary ratchet wheel will be provided with ten teeth, and the others will be provided with twelve teeth each, comprising ten "working" teeth, and two additional 25 teeth to compensate for the lost motion of said discs incident to operation thereof by engagement of plate 61 with the teeth thereof. The pivot mounting of plate 61 accommodates the passage of the pins 63 thereunder, and the spring contacts 30 72 are sufficiently flexible to permit the long pins 63 to move past the same.

It will thus be seen that this invention provides a control by which a dispenser may be actuated at intervals in response to any predetermined number of operations of the associated coin controlled device, to provide a stimulus to users of the device based on the knowledge that rewards are dispensed during a sequence of operations entirely independently of skill or of the result obtained by operation of the game device per se.

What is claimed as new and useful is:—

1. Means for controlling a dispenser associated with a coin controlled device to operate said dispenser once for each predetermined number of operations of said coin controlled device, comprising primary and secondary members rotatable step-by-step, said secondary member being associated with said primary member to normally rotate one step for each revolution of said primary member, means for actuating said primary member, a control switch comprising spaced resilient contacts, means carried by said secondary member for pressing said contacts into engagement, and means cooperating with said first named actuating means for rotating said secondary member one step upon the operation of the primary member immediately following engagement of said contacts.
2. Means for controlling a dispenser associated with a coin operated device to operate said dispenser once for each predetermined number of operations of said device, comprising a primary member shiftable step-by-step, a secondary step-by-step member normally shifted one step for each predetermined series of steps of said primary member, a normally open switch, means carried by said secondary member for closing said switch at a predetermined position of said secondary member, and means for shifting said secondary member one step upon operation of the primary member immediately succeeding closing of said switch.
3. Means for controlling a dispenser associated with a coin operated device, comprising a

rotatable ratchet, a pawl for actuating said ratchet step-by-step, a second rotatable ratchet normally rotated step-by-step in response to repeated actuation of said first ratchet, control means actuated by said second ratchet at a predetermined position thereof, and means associated with said pawl for shifting said second ratchet from control-actuating position upon the actuation of the pawl immediately succeeding shifting of said second ratchet to control-actuating position.

4. Means for controlling a dispenser associated with a coin operated device, comprising a member rotatable step-by-step, a second member normally rotatable step-by-step in predetermined delayed relation to first member, actuating means carried by said second member, a control energized by said means when said second rotatable member is at a predetermined position, and means for shifting said second rotatable member independently of its normal relation to said first member upon the first actuation of said first rotatable member following actuation of said control.

5. Means for controlling a dispenser associated with a coin operated device, comprising a series of members rotatable step-by-step in predetermined counting relation, means for actuating one of said members, control means comprising a stationary part and a part carried by another of said members, said parts interengaging in actuating relation when said last named member is at a predetermined position, said actuating means being normally disassociated from said last named member, and means carried by said actuating means for rotating said last named member immediately succeeding interengagement of said parts.

6. Means adapted to control a dispenser associated with a coin operated device, comprising an actuator, a member shifted step-by-step by said actuator, a step-by-step secondary member normally shifted one step upon each cycle of operation of said first member, control means operated by said secondary member when said secondary member is in predetermined position, and means cooperating with said actuator to shift said secondary member one step upon operation of said actuator following operation of said control.

7. Means adapted to control a dispenser associated with a coin operated device, comprising a series of rotatable members including a primary member and an operating member normally rotatable one step for each rotation of said primary member, an actuator for said primary member, a controller, a member for actuating said controller carried by said operating member, and means for consecutively shifting said operating member and controller actuating member with said primary member upon actuation of said actuator succeeding operation of said controller by the actuating member therefor.

8. Dispenser control means comprising a series of members normally rotatable step-by-step and including a primary member and an operating member normally rotatable in predetermined relation to said primary member, a control, means carried by said operating member adapted to actuate said control when in a predetermined position, and means for shifting said operating member consecutively with said primary member when said operating member is adjacent said predetermined control actuating position.

9. Dispenser control means comprising primary and secondary members normally rotatable step-

5 by-step in counting relation, an actuator engaging said primary member, a control, means carried by said secondary member for actuating said control when in predetermined position, and a projection carried by said secondary member and engageable by said actuator to shift said secondary member independently of its normal relation to said primary member when said secondary member is in said predetermined position.

10. Dispenser control means comprising primary and operating members normally rotatable step-by-step in counting relation, an actuator engaging said primary member, control means actuated by said operating member, and means engageable by said actuator for rotating said operating member independently of said counting relation following each operation of said control.
